UNITED STATES PATENT OFFICE.

SAMUEL GIBBY, OF BOSTON, MASSACHUSETTS.

SIGN.

Specification of Letters Patent. Patented Sept. 14, 1920.

1,352,661.

Application filed June 24, 1918. Serial No. 241,461.

To all whom it may concern:

Be it known that I, SAMUEL GIBBY, a citizen of the United States, residing at Boston, in the county of Suffolk, in the State of Massachusetts, have invented a certain new and useful Improvement in Signs, of which the following is a specification, reference being had to the accompanying drawings.

This invention relates generally to signs or signals of the class used commonly on automobiles, at the centers of intersecting streets, in parkways to indicate the proper direction of movement of vehicles, etc., my purpose being to provide a simple and inexpensive form of signal or sign in which special provision is made for readily changing the sign proper as well as for illuminating the same when it is to be used at night or in otherwise dark places. My said invention also includes visible means whereby a distinctive identifying mark or sign is provided, as I will explain more specifically hereinafter.

My invention is clearly illustrated in, and by means of the annexed drawings, in which the Figure 1 is a rear or exposed side elevation of a signal or sign embodying my present improvements and Fig. 2 is a transverse, vertical, section taken on the line 2--2 of said Fig. 1.

Fig. 3 is a top view of the same. Fig. 4 is a rear or exposed side view of the sign showing also, as a distinctive feature thereof, the identification means referred to above. Fig. 5 is a relatively enlarged, sectional, view of the exposed number plate and transparent sheet of glass at the rear of said number plate.

In these drawings the reference numeral 10 indicates a housing, having grooved, vertical, ways in its opposite sides in which a sheet 12 of semi-opaque material such as milky white "cathedral" glass may be slid; also in close relation to said glass a stiff metallic plate 11 in which is cut, after the manner of a stencil plate, any desired numbers, letters or other characters. Within the housing 10, at the rear of the glass plate 12, I provide one or more lights by means of which those portions of the glass 11 which are exposed by the cutting away of the stencil plate will be illuminated at night. This can be done successfully by oil lights but I prefer to provide incandescent electric lights 13; for such illumination the electric light bulbs being wired in circuit with a suitable

source of electrical energy, such as a battery 14 which may be located in close relation to the described sign, or at any other convenient place.

During the day time the stencil openings are backed by the white, or approximately white, sheet of glass 11, the white characters being then clearly defined against the preferably black face of the stencil plate.

At or near the lower front portion of the housing 10 are openings 15-16 in which may be placed sheets of colored glass such as, for example, red and green which will be plainly visible by a following car, if the device is applied to an automobile and, by preference, I also provide a third opening 17 located in near relation to the opening 15, as here illustrated, the opening 17 being for use as a distinctive, or personal, signal by the owner of the vehicle as, for example, when said vehicle is parked with a large number of similar vehicles while its owner is attending the opera, or other function, at night, and it is difficult to select his particular car. By placing some distinctive character, symbol, or letter on the illuminated field of said opening 17, the owner is enabled to readily identify his car even if it be located a considerable distance away.

In connection with the openings 15 and 17 I have provided a shield 18 which is pivoted at 19 and is adapted to be swung from its normal or closed position over the opening 17 to a temporary position over the adjacent opening 15, as seen in Fig. 4 of the drawing in order to expose the special signal.

The described construction of the device, whereby the stencil 11 may be readily slipped into or removed from the ways in the housing, renders it very easy and cheap to substitute new stencils whenever it is desirable or necessary to change the figures or lettering of said stencils.

Having thus described my invention, I claim:

1. The combination with a casing and light emitting means in said casing of a stencil plate and a semi-transparent plate coextensive therewith, both plates forming part of a wall of said casing, and an apertured casing wall outside of said plates light-transmitting, differently colored closing means for said apertures, adapted to carry indicating marks; movable covering means intermediate said closing means, and

adapted to selectively and concealingly engage with said closing means.

2. The combination with a casing of a plate adapted for the passage of light forming a section of a wall of said casing and removably secured therein, indicating marks on said plate, and a translucent covering plate coextensive with said first mentioned plate, an apertured section on said wall and 10 outside said plates, differently colored clos-

ing means filling said apertures, and indicating means located within said apertures, and secured to said closing means, movable covering means intermediate two adjacent closing means, and adapted to selectively 15 and concealingly engage with one of said adjacent closing means, and light emitting means in said casing.

SAMUEL GIBBY.
